ATTORNEY.

UNITED STATES PATENT OFFICE.

HENRY PARKIN, OF PHILADELPHIA, PENNSYLVANIA, ASSIGNOR OF ONE-HALF TO
GEORGE G. MEELEY, OF PHILADELPHIA, PENNSYLVANIA.

STARTER APPLICABLE TO MAGNETOS.

1,328,892.

Specification of Letters Patent. Patented Jan. 27, 1920.

Application filed January 2, 1919. Serial No. 269,387.

To all whom it may concern:

Be it known that I, HENRY PARKIN, a citizen of the United States, residing at Philadelphia, in the county of Philadelphia 5 and State of Pennsylvania, have invented certain new and useful Improvements in Starters Applicable to Magnetos, of which the following is a specification.

The principal objects of the present invention are, first, to provide a starter easily applicable to existing magnetos, to provide a compact, durable and efficient starter for magnetos, to provide for reliably locking the starter when its spring is being set and 15 for positively releasing it thereafter, and to avoid interference with the operation of the magneto in case of accident to the starter.

To these and other ends hereinafter set forth the invention comprises the improvements to be presently described and finally claimed.

In the description reference will be made to the accompanying drawings forming part 25 hereof and in which—

Figure 1, is a side elevation showing a form of the invention.

Fig. 2, is an end view with parts removed, and

Fig. 3, is a view of one of the parts detached.

In the drawings 1, is a frame and 2, is a drive-shaft, and these are practically provisions of all usual makes of magnetos. 35 Usually the drive shaft receives one member of a driving coupling which is keyed on otherwise made fast on it. According to my invention the coupling member is taken off the drive shaft and the drive shaft 2, receives the rotary elements of the starter, and the frame 1, receives a bracket 3, which carries the other parts of the starter, and so my starter may be easily, rapidly and inexpensively applied to existing magnetos. 45 without requiring any alterations therein.

The driven member 4, is keyed on otherwise fast on the shaft 2, and it is provided with a laterally extending hub 5, upon which is rotatably mounted the driving member 6, and the nut and washer 7, serve to retain these parts in place. In suitable annular confronting grooves 8 and 9, formed in the faces of the members 4 and 6, are arranged a starting spring 10, and a buffer spring 11. Projections 12 and 13, on the

elements 4 and 6, engage the ends of these springs and the spring 10, may be sufficiently stiff to drive the magneto without substantial compression; although this spring is compressed when the car is 60 cranked manually and its recoil operates to start or spin the magneto, it being understood that the driving member 6, is driven from the engine-shaft for example, through the coupling lugs 14, and by gearing not 65 shown. The bracket 3, is provided with a stud 15, to which is centrally pivoted a latch 16, one end 17, of which is adapted to engage and disengage a tooth or any one of several teeth 18, on the driven member 4, 70 and the other end of which is acted upon by a positioning lock and by shifting means. The shifting means are not shown but they may comprise a wire, rod or the like attached to the eye 19, and operated by hand 75 to cause the latch to engage a tooth or notch 18. The positioning lock comprises a spring post 20, projecting from the bracket 3, and provided with a roller co-operating with a cam face 21, to hold the latch in 80 engagement with a tooth or notch and co-operating with a depression 22, for holding the latch out of action. There is a stud or roller 23, on the latch and when the latch is in engagement with a tooth 85 or notch it is disposed in line with a tap-pet 24, on the driven member 6, which acting on the stud or roller serves to throw out the latch as the member 4, is spun by the release of the spring 10.

The starter can be installed upon any existing or usual magneto by replacing the usual coupling member on the shaft 2, with the parts 4, and 6, and their accessory springs, for these parts are not only elements 95 of a starter but also, by reason of their combined thinness, in effect constitute a coupling element in the sense that they can replace the usual coupling member. The bracket 3, with the parts which it carries 100 is attached as by screws to the frame 1. 112 necessary and in order to meet the requirements of different usual magnetos, brackets having studs 15, and spring posts 20, of different lengths may be provided. In starting the operator puts the latch 17, in action manually so that it engages a tooth or notch 18, in the driven element 4, and holds the latter against forward rotation, and the cam face 21, holds the latch in that position. 110

When the engine is cranked the driving member 6, is turned forward, compressing the spring 10, and causing a tappet 24, by striking the stud 23, to throw out the latch 16, whereupon the spring 10, being released turns the driven element 4, and spins the magneto. The positive lock mechanism holds the latch out of action, because the spring post 20, or more accurately the roller 10 on its end, enters the depression 22, and remains there until the engine is again to be started, and then the described operations are repeated. By facially grooving each of the driving and driven members and so making a part of the cavity for the spring in each, important advantages are obtained among which reference may be made to the following: The spring is free to work without binding, ample depth of stock is provided 20 for supporting and attaching the projections 12 and 13, and ample width is provided for supporting the tappets 24, and for affording strong teeth 18, and no machine work is necessary on the grooves.

25 It will be evident to those skilled in the art that the invention may be embodied in forms other than those described and illustrated in detail, and consequently the invention is not limited in that regard or in 30 any other way than the appended claims and the state of the prior art may require.

What I claim is:

1. A starter applicable to magnetos comprising the combination of a driven member having a laterally projecting hub, a driving member revoluble on said hub, a spring driving connection between said members, said driven member having a

notched portion, a laterally disposed bracket adapted to be secured to a face of the magneto, a latch arm pivoted to said bracket intermediate its ends, said latch arm's, ends, said latch arm being provided on its inner end with a biased nose adapted to engage said notch and at its opposite end with two spaced noses, and a spring post secured to said bracket and extending laterally outward therefrom to engage said last two noses.

2. A starter applicable to magnetos comprising the combination of a driven member having a laterally projecting hub, a driving member revoluble on said hub, a spring driving connection between said members, said driven member having a notch in its periphery, a bracket having a base portion to be secured to the face of the magneto and a laterally extending cylindrical pin receiving portion, a pin, a latch arm pivoted to said pin intermediate its ends, said arm having at its inner end a nose adapted to engage said notch and at its opposite end irregular faces, a flat spring secured to the base of the bracket and extending laterally outward therefrom, said spring having at its ends a post adapted to engage said irregular faces.

3. In a starter applicable to magnetos a coupling member consisting of driving and driven members whereof each is provided with a facial groove semi-circular in cross-section and constituting a part of a spring-housing and a spirally wound spring arranged partly in each groove, substantially as described.

HENRY PARKIN.
